KNITTING METHOD AND MECHANISM

Louis Hirsch, Weehawken, N. J., assignor to Louis Hirsch Textile Machines, Inc., New York, N. Y., a corporation of New York

Application May 31, 1935, Serial No. 24,179

6 Claims. (Cl. 66—89)

This invention relates to fashioned hosiery fabric and, in particular, to those parts thereof at which fashioning or narrowing occurs. Its object is to provide a novel, run-proof loop construction in the needle wales to which the innermost one or two loops are transferred and in the intermediate sinker wale or wales of the narrowed courses.

As is well known the usual method of narrowing is to transfer a certain number of loops adjacent the edges of the fabric inwardly either one or two needles, as the case may be, depending upon whether one needle or two needle narrowing is desired. After the loop transferring operation is completed each of the needles involved, except the innermost one or two, still carries a single loop, whereas the innermost one or two needles still support the loops originally formed upon them and the newly transferred loops as well. Occasionally the narrowing points fail to effect the transfer of the loops to these needles or may cause the needles to split the thread. In the former case a dropped stitch will result which will develop into a run. In the latter case the loops of the following course will be pulled through the split thread so that while the transferred loop will be anchored to the following course after a fashion the anchorage will be weak and the thread will almost certainly break during wear, if not immediately. At best the loop structure at this point and, consequently, the strains upon it are abnormal, a condition conducive to runs even when the loop transferring has been perfectly performed.

By this invention the fabric is made run-proof upwardly in these particular needle wales and downwardly in the intermediate sinker wales by a novel loop transferring operation in which the innermost one or two loops are not only transferred from the original needles to others but are carried around an additional needle as well, as will be described. These special loops superposed upon normal loops form the fashioning marks characteristic of high quality hosiery and the eye is unable to distinguish the fabric from that in which the narrowing has been done by the conventional method.

The novel loop construction and a mechanism for producing it is shown in the drawings, of which

Figure 1 represents a full fashioned stocking in which the narrowing is indicated by the well known fashioning marks;

Fig. 2 is an enlarged view of a fragment of

fabric including the loop construction of this invention in single needle narrowing;

Fig. 3 is a similar enlarged view of a fragment of fabric including two needle narrowing in accordance with the invention;

Fig. 4 is a front view of a narrowing comb and a special auxiliary narrowing point adapted to perform the modified one needle narrowing of the fabric shown in Fig. 2;

Fig. 5 is a side view of the device of Fig. 4 partly in section on the line 5—5 of Fig. 4 viewed as indicated by the arrow;

Fig. 6 is a front view of the device of Fig. 2 showing the relative positions of the inside narrowing point and its associated auxiliary point at the end of the narrowing operation;

Fig. 7 is a cross-section of these narrowing points on the line 7—7 of Fig. 4 viewed as indicated by the arrows;

Fig. 8 is a cross-section of these narrowing points along the line 8—8 of Fig. 6 viewed as indicated by the arrows;

Fig. 9 is a front view of the narrowing comb and auxiliary points required for the two needle narrowing shown in Fig. 3;

Fig. 10 is a view of the same device with the auxiliary points in the positions assumed at the end of the narrowing operation;

Fig. 11 is a cross-section of the points on the line 11—11 of Fig. 9 viewed as indicated by the arrows; and

Fig. 12 is a cross-section of the same points along the line 12—12 of Fig. 10 viewed as indicated by the arrows.

In Figure 1 the usual narrowed areas to which this invention is applicable are indicated by the typical fashioning marks such as 1 and 2. These, as is well known, occur in the wales of the narrowing courses in which transferred loops are superposed upon normal loops. This invention is concerned solely with the courses in which such transfer of loops occurs and solely with the one or two innermost loops which are superposed upon normal loops.

The usual practice in narrowing is to simply remove the loops affected from the needles upon which they are formed and deposit them upon the next or the second needle. Each transferred loop is still supported by a single needle. In this invention all of the loops with the exception of the one or two inner loops are formed and transferred in the usual way. For example, in Fig. 2 which illustrates fabric in which each narrowing is limited to a single needle the loops 3, 4 and 5 which were originally formed upon needles 6, 55

7 and 8 respectively, are transferred one needle to the right in the usual manner so that they now hang upon needles 7, 8 and 9 respectively. The inside loop 10 is also transferred to the right from needle 9 to the needle 11 and, in addition, it is carried around the next needle 12. The result is that this loop 10 will be interlinked with two loops of the other needle wales in the following course and needle wales 13 and 14 and 10 sinker wale 15 will be run-proofed at this course.

When the fabric is narrowed again in a similar manner corresponding wales will be similarly run-proofed. Consequently, by this invention runs which so frequently start in these wales in the 15 narrowing courses are eliminated without affecting the appearance of the fabric or the general method of making it.

If it is desired to narrow the fabric at the rate of two needles per narrowing operation instead of 20 one needle, the loops are transferred inwardly two needles instead of one. The two innermost loops which are to be superposed upon normal loops are each transferred inwardly two needles and each is carried around the next needle also. 25 This is shown in Fig. 3 in which loops 16, 17 and 18 which were originally formed upon needles 19, 20 and 21 respectively, have been transferred two needles to the right and deposited upon needles 21, 22 and 23 respectively. Loop 24 has also been 30 transferred two needles and deposited upon needle 25 and, in addition, it has been carried around needle 26. Similarly loop 27 has been transferred two needles, from needle 28, and deposited upon needle 26 and has also been carried around the 35 following needle 28. The three needle wales 29 and 30 and 31 are thereby run-proofed and the two sinker wales 32 and 33 are run-proofed downwardly. Otherwise the structure of the stocking is unchanged and its appearance un- 40 altered. Succeeding narrowing operations performed in the same manner will run-proof corresponding wales.

To knit the fabric of this invention requires a 45 modification in the narrowing mechanism. One form suitable for single needle narrowing is shown in Figs. 4-8. In this the narrowing comb is shown at 34. This may be standard in all respects with the exception that the innermost narrowing point 35 is of special construction in that its inside 50 wall 36 is partly cut away as shown at 37. The cross-section of the point shown in Fig. 8 illustrates this clearly. The narrowing comb 34 may be mounted upon the usual rod and operated in the usual manner by the usual mechanism.

55 In addition, an auxiliary narrowing point 39 is mounted upon a narrowing rod 40 by means of a suitable bracket 41. Narrowing point 39 is so shaped that its end 42 may enter and lie within that part of the groove 43 of narrowing point 35 of which the side wall 36 has been cut away as shown in Fig. 5 and is provided with a groove 44 adapted to engage with the beard of the needle. Narrowing rod 40 is mounted similarly to the other narrowing rods so that when the narrowing 60 machine dips to remove the loops from the original needles and then shifts them over, preparatory to placing them upon the new needles, narrowing rod 40 will do likewise, auxiliary point 39 remaining in the groove 43 of point 35 and 65 moving with it. However, when the longitudinal movement of the narrowing comb 34 is completed and before the machine dips the second time to place the loops upon the new needles, auxiliary point 39 is independently moved an additional needle, as shown in Figs. 6 and 8, to ex-

tend the loop over an additional needle. Then when the second dip occurs this loop 10 will not only have been transferred from its original needle 9 but will be deposited upon two other needles 11 and 12 instead of upon needle 11 alone, as shown in Fig. 2.

For effecting the two needle narrowing shown in Fig. 3 the narrowing mechanism is modified as shown in Figs. 9-12. The next to the innermost narrowing point 44 is of a construction 10 similar to that already described for point 35, that is to say, its inside wall 45 is similarly cut away. Associated with this point in the manner already described with respect to point 35 is an auxiliary point 46 similar to auxiliary point 39. 15 These two points cooperate to transfer the next to the innermost loop 24 not only two needles to the right to needle 25 but also to carry it around needle 26.

The innermost narrowing point 47 of the narrowing comb, instead of being provided with the usual groove or the partial groove already described, is substantially flat, as best shown in Fig. 11 so that it will not interfere with the inward motion of special point 46. Associated 25 with flat point 47 in a manner similar to that already described is a second auxiliary point 48 also similar to 46. This pair of points 47 and 48 cooperate to effect the transfer of innermost loop 27 two needles inwardly from needle 28 and 30 its deposit upon needle 26 and to carry it around the following needle 28. The auxiliary points 46 and 48 move together and, consequently, may be carried by the same arm 49. As previously explained in connection with the one needle narrowing of Fig. 2, the narrowing comb and the auxiliary points initially move together until the loops are in position to be deposited upon needles 25 and 26 respectively, whereupon the two auxiliary points 46 and 48 move inwardly an additional needle, as shown in Figs. 10 and 12, extending the loops over needles 26 and 28 respectively. The subsequent dipping of the narrowing mechanism will deposit these loops upon these needles each of which, of course, already 45 carries a normal loop.

The loop construction described may be advantageously employed wherever narrowing occurs, both in the leg and the foot, or it may be confined to one or more narrowed areas if desired, 50 and the remainder of the narrowing performed in the conventional manner. The same mechanism can be used for conventional narrowing by simply throwing out of action the mechanism 55 which produces the independent movement of the auxiliary points described above.

What I claim is:

1. The method of narrowing knitted fabric which consists of transferring a plurality of marginal needle loops of a course inwardly each from the needle upon which it is formed to another needle and simultaneously transferring a loop adjacent the innermost one of said plurality of loops inwardly to two other juxtaposed needles. 65

2. The method of narrowing knitted fabric which consists of transferring a plurality of marginal needle loops of a course each from the needle upon which it is formed to the adjacent needle inwardly and simultaneously transferring the loop adjacent the innermost one of said plurality of loops inwardly to the adjacent and also the following needle. 70

3. The method of narrowing knitted fabric which consists of transferring a plurality of 75

needle loops of a course each from the needle upon which it is formed to the second needle inwardly and simultaneously transferring the two loops adjacent said plurality of loops each to the second needle inwardly and also to the needle inward of said last mentioned second needle.

4. In the narrowing mechanism of a flat knitting machine the combination of a longitudinally movable narrowing comb provided with a plurality of narrowing points and an auxiliary point engageable with one of said narrowing points and movable therewith and also independently movable longitudinally of the machine.

5. In the narrowing mechanism of a flat knitting machine, the combination of a longitudinally

movable narrowing comb provided with a plurality of narrowing points and two auxiliary points engageable with a juxtaposed pair of said narrowing points and movable therewith and also independently movable longitudinally of the machine. 5

6. In the narrowing mechanism of a flat knitting machine the combination of a longitudinally movable narrowing comb provided with a plurality of narrowing points and two auxiliary 10 points engageable with a juxtaposed pair of said narrowing points and movable therewith and also independently movable as a unit longitudinally of the machine.
